CONVERTIBLE STEPLADDER

Raymond R. Salisbury, Ann Arbor, Mich.

Application July 8, 1946, Serial No. 682,015.

1 Claim. (Cl. 228—68)

1

The invention relates to ladders and more particularly to the type of ladder which is adapted to be convertible from a step ladder to an extension ladder.

An object of this invention is to provide a convertible step and extension ladder which may readily be converted from a step ladder into an extension ladder by partially rotating the back of the step ladder upwardly and engaging it with the front ladder to provide an upward extension thereof.

Another object of this invention is to provide an improved convertible step and extension ladder which includes a front step ladder section and a runged rear support section, pivotally connected at their upper end whereby the rear section may be rotated to provide an extension of the front ladder section and an improved wedge shaped interlocking joint or connection carried partially by the front section and partly by the rear section, engageable in the extended position of the ladder.

Still another object of this invention is to provide an improved locking means for connecting the extending ladder sections together whereby the locking means consists of a flanged wedge shaped member having a locking wedge fixed on one ladder section and a cooperating wedge shaped member carried by the other ladder section and a resilient or spring pressed keeper on the latter member engageable with the locking wedge on the first member for holding the adjacent ladder sections in extended position whereby the resilient keeper may be readily disengaged by an operator for folding the ladder sections to a step ladder position.

With the above and other objects in view, my invention consists in the arrangement, combination and details of construction disclosed in the drawings and specification, and then more particularly pointed out in the appended claim.

In the drawings,

Figure 1 is a side elevation of a convertible step and extension ladder constructed according to an embodiment of my invention.

Figure 2 is a rear elevation of the ladder,

Figure 3 is a fragmentary rear elevation of the ladder in extended position,

Figure 4 is a horizontal section taken on the line 4—4 of Figure 3,

Figure 5 is a detail side elevation of one clamping member separate from the ladder,

Figure 6 is a detail side elevation of the other clamping member separate from the ladder,

2

Figure 7 is a perspective fragmentary view of an extension ladder attachment.

In the drawings the numeral 10 designates generally a convertible step and extension ladder constructed according to an embodiment of this invention. The ladder consists of a front ladder section 11 and a rear ladder and supporting member 12 hinged together near their upper ends. The front ladder section consists of a pair of elongated side or supporting members 14 and rungs 15, supporting members 14 and rungs 15 supported therebetween. The side supporting members 14 are maintained in an upwardly convergent relation whereby the rungs 15 at the lower end thereof are longer than the upper rungs, the rungs being successively shorter along the length of this lower ladder section 11.

The rungs 15 are secured to the side members 14 by engaging in transverse grooves or notches 16 therein and are strengthened by rods 17 connected to the side members 14 on each end thereof directly below each rung or step 15 and support the step 15 by engaging below a block 18 on the center of each step 15 below the longitudinal median of the step 15.

Spaced downwardly from the upper end of the ladder section 11 on each member 14 approximately below the highest step 15, there is secured a hinge member 19. The hinge member 19 comprises a clamping strap 20 which encircles the member 14 and is secured thereon by rivets 21 or other suitable fastening means. A rearwardly extending lug or apertured ear 22 is fixed to or formed on the strap 20 on the rearward side thereof and is adapted to provide a section of hinge barrel to which the rear section 12 may be hingedly attached.

The rear ladder or supporting member 12 is formed of a pair of parallel side-supporting members 24 which support a series of rungs 25 thereon. The rungs 25 are formed of rounded sections or rods, the ends of which may be imbedded in sockets or openings 26 in the side members 24. The rungs 25 are of equal length substantially equal to the average width of the rungs 15 of the front ladder section 11, whereby the upper end of the rear section 12 is wider than the upper end of the front section 11.

Hinge members 27 are carried by the side members 24 at their upper ends and are formed of a clamping strap 28 which encircles the member 24 and is fastened thereto by rivets 29 or other suitable fastening means. A forwardly extending apertured lug or ear 30 is fixed to or formed 55 on to the strap 28 and a hinge pin 31 extends

through the ears 22 and 30 for hingedly connecting the ladder members 11 and 12 together. A wing nut 32 secures the rod or pin 31 in position and may be tightened or loosened by an operator for adjusting the friction on the hinge members 19 and 21.

In the lower folded or step ladder position, as shown in Figure 1, the rear section 12 provides a support for the front ladder section 11 and is held against sliding outwardly by a chain 34 fixed at one end to the section 11 as by a link 35 and is detachably connected to the member 12 by a spring pressed clamp 36 secured to the chain 34 engaging in eye bolts 37 fixed in the side members 24.

For latching the front and rear ladder section 11 and 12 together in the extended or aligned position thereof, I have provided a pair of inter-engaging locking members 38 and 39 carried by the front and rear sections 11 and 12 respectively.

The locking member 38, fixed on the side members 14 of the front ladder section 11 is formed of a flat strip of metal having a pair of oppositely disposed rearwardly diverging flanges 40 and an outwardly extending ear 41 on each end thereof. The ears 41 are adapted to be bent around the edges of the member 14 with the inwardly bent flanges 40 on the outside of the members 14. Between the flanges 40 there is secured a rearwardly and outwardly extending wedge shaped keeper 42 fixed to the member 38 by rivets 34 or other suitable fastening means.

The locking member 39, fixed on the members 24 of the rear ladder 12, is adapted to engage in and lock onto the locking member 38. The locking member 39 is formed of a flat strip of metal having a pair of oppositely disposed rearwardly diverging inwardly inclined flanges 46. A pair of ears 47 are fixed on opposite ends of the members 39 for attaching the member 39 to the side ladder members 24. Between the flanges 46 there is fixed a flat elongated hook member 45 fixed at its forward end to the member 39 by a rivet 48 or other suitable attaching means, and is adapted to be engaged over the keeper 42. The members 39 are fixed on the inside of the ladder side members 24 in such a manner as to engage in and become latched in the members 38 fixed on the outside of the front ladder side members 14.

In the use and operation of this ladder 10 to convert the ladder from a step ladder as shown in Figures 1 and 2, the hook 36 is disengaged from the eye 37 and the rear ladder 12 is pivoted about the hinge bolt 31 until the latch member 39 is engaged in latch member 38 as seen in Figure 3 and the hook 45 engages with the wedge lock member 42 securing the front and rear ladder sections 11 and 12 together. To disengage the ladders 11 and 12 it is necessary only for an operator to move the keeper 45 out of engagement with the wedge 42 with his fingers and rock the rear member 12 rearwardly and downwardly to its original position where the clamp 36 may again be engaged with the eye 37 in the step ladder position.

A basket 50 may be provided to be supported on the ladder 10. This basket 50 is formed of

a wire body 51 having forwardly extending handles or rods 52. The rods 52 extend forwardly over the top rung of the ladder, are then reverted forwardly and downwardly where they are bent outwardly near their terminals in a right angularly bent section 53 engageable with the side members, as 14, for securing the basket 50 thereon.

In Figure 7 there is shown an attached extension ladder section 60 which may be used to lengthen the extended step ladder 10. As the sides 24 of the rear and upper section 12 are parallel, an extension ladder 60 may be secured to the upper extended end thereof. The extension is provided at its lower with a pair of oppositely disposed U-shaped channel sections 61 fixed to the side members 62 of the ladder 60 by bolts 64 and which encompass the side members 62 and extend downwardly past the ends of the members 62 to encompass the side members 24 of the ladder section 12. The ladder extension 60 may be attached when the ladder 10 is in its extended position.

I do not mean to confine myself to the exact details of construction herein disclosed, but claim all variations falling within the purview of the appended claim.

What I claim is:

In a combination step and extension ladder having hingedly connected front and rear section a releasable locking means for locking the front and rear ladder sections in aligned position, said locking means comprising locking members carried by one of said ladder sections, rearwardly diverging flanges on said locking member, a wedge-shaped keeper fixed to said member between said flanges and spaced inwardly from the ends thereof, locking members carried by the other of said ladder sections, rearwardly diverging flanges on said latter members slidably engaging said first mentioned flanges and spacing said latter members from said first mentioned members, a spring-pressed hook on said latter members between the flanges and ends thereof engageable with said keeper for locking said ladder sections together, and a hook releasing member carried by said hook extending beyond one end of said locking members.

RAYMOND R. SALISBURY.
